UNITED STATES PATENT OFFICE.

ALBERT G. VOLTZ, OF TULSA, OKLAHOMA.

HACK SAW.

Application filed March 20, 1922. Serial No. 545,153.

To all whom it may concern:

Be it known that I, ALBERT G. VOLTZ, a citizen of the United States, and resident of Tulsa, county of Tulsa, State of Oklahoma, have invented a certain new and useful Improvement in Hack Saws, of which the following is a complete specification.

This invention relates to hack saws, and more especially to hack saw frames, and my object is to produce a construction which will accommodate hack saw blades of different lengths; in which the blade can be set to cut a projection in substantially the plane of the surface from which the projection extends; or to cut obliquely with respect to the plane of the frame; and by which the blade can be disposed at varying distances from the back of the frame and either parallel therewith or in converging relation thereto, the last-named adjustment being desirable as it permits of a cut being made from the inside of a tube or hole.

With these general objects in view and others as hereinafter appear, the invention consists in certain novel and useful features of construction and organization as herein-after described and claimed; and in order that it may be fully understood, reference is to be had to the accompanying drawings, in which:

Figure 1 is a side elevation of a hack saw embodying the invention;

Figure 2 is a top view of the same;

Figure 3 is a section on the line III—III of Figure 1;

Figure 4 is a section on the line IV—IV of Figure 1;

Figure 5 is an enlarged section on the line V—V of Figure 1;

Figure 6 is an enlarged section on the line VI—VI of Figure 1;

Figure 7 is a detail section taken through the saw blade when arranged to cut parallel with but offset with respect to the back of the frame;

Figure 8 is a similar detail with the blade set to cut at an angle with respect to the side of the frame;

Figure 9 is a section taken on the line IX—IX of Figure 2;

Figure 10 is a detail perspective view showing a part of one of the angle arms of the device;

Figure 11 is a detail showing the connection between one end of the saw blade and one angle arm of the frame;

Figure 12 is a section on the line XII—XII of Figure 11;

Figure 13 is a section on the line XIII—XIII of Figure 11;

Figure 14 is a detail perspective view of one of the brackets which support the adjustable saw-carrying holders;

Figure 15 is a perspective view of an octagonal cap for locking one of the holders at different points of its rotary adjustment;

Figure 16 is a view corresponding to Figure 14, but of the other bracket;

Figure 17 is a fragmentary view of the saw-carrying holder for use with the bracket of Figure 16;

Figure 18 is a side elevation partly broken away, showing the construction and arrangement of parts whereby a saw blade can be arranged in close proximity with and parallel to the back of the frame or set at a forwardly converging angle with respect to the back of the frame;

Figure 19 is a section on the line XIX—XIX of Figure 18; and

Figure 20 is a modified construction disclosed partly in side elevation and partly in section and illustrative particularly of a cheaper construction and how certain adjustments are made to accommodate blades of different length.

Referring now to the drawings, 1 indicates the handle of a frame of a hack saw, and secured as at 2 to said handle is the back 3 of narrow channeled construction for the greater portion of its length, said channeled back being increased in depth and width as at 4, (Figures 1 to 18). It is provided in the lower edges of the side walls with equi-spaced notches 5, and at the extreme end of portion 4 with lugs 6 connected by a cross-pin 7. A relatively short channel member 8, corresponding substantially in cross sectional form to the back, fits snugly within the enlarged portion 4 and is provided with a plurality of notches 9 in its lower edge, any one of which is adapted to be engaged by the cross-pin 7 mentioned, for the purpose of holding the member 8 at the desired adjustment. The channel member 8 projects beyond the front end of the

2
back, and its walls are extended downward below the walls of the back and one of the extensions of said walls is equipped with a headed lug 11 and forward thereof the extensions are more widely spaced, (see Figures 2 and 3) to produce a pair of lugs 12 equipped with a cross-pin 13.

A pair of angle arms 14 constituting parts of the frame, are adapted to be fitted with 10 their long ends (Figures 1 and 18), or their short ends (Figure 20), in the channel of the back and in the channel member 8 respectively, and at the inner side of the angle formed by said arms are provided laterally- 15 projecting lugs 15 having notches 16, and the ends of said arms are formed in their opposite sides with cavities 17 spaced at equal distances apart. To secure said angle arms to the back, the cross-pin 13 engages 20 one of the recesses 16, and a similar cross-pin 18 engages the corresponding recess of the other arm, the cross-pin 18 connecting the ends of an inverted U-shaped clip 19 fitted slidably on the back 3. The laterally- 25 projecting lugs 15 by bearing against the inner sides of lugs 12 and of the clip 19, tend to prevent lateral movement of the angle arms and to provide wider bearings on the pins 13 and 18. The ends of the 30 angle arm near the handle end of the back, are provided with opposite pins 16^a, the set of such pins of the end engaging the channeled back, engaging opposite notches of the back to prevent longitudinal slippage of 35 the angle arms.

A right-angle shaped bracket 20 is formed with a keeper 21 fitting slidingly on the end of the adjacent angle arm 14, and a set screw 22 carried by said keeper is adapted for engagement with one of the cavities 17 to 40 secure the bracket against accidental movement. A similar bracket 23 is provided with a keeper 24 to fit on the adjacent end of the other angle arm, and a set screw 25 is carried by said keeper for engagement with one of the cavities 17 of said angle arm.

At the opposite end of the angle bracket 20, a tubular bearing 26 is secured as at 27, the said bearing at its ends being of octagonal form as at 28. A similar bearing 29 is secured as at 30 to the angle bracket 23, and at one end is formed with an octagonal socket 31. A rotatable saw holder 32 fits in the bearing 29, and a rotatable holder 33 fits in the bearing 26, each of said holders having offset angle arms 34 having laterally projecting headed lugs 35 and corresponding depending lugs 36 projecting at right angles to lugs 35. The blade 37 is provided with 50 the customary openings for engaging the lugs 35 or 36 according to the adjustment of the holders. To provide for securing the holder 32 at different points of rotatable adjustment, the latter is provided with an octagonal head 38 for engagement in the

octagonal socket 31. For the same purpose the holder 33 is threaded as at 39 and provided with a longitudinal groove 40, and fitting on said stem is an octagonal cap 41 engaging the adjacent octagonal head of 70 bearing 26, the cap having a tongue 42 engaging the groove 40 to prevent rotatable movement of the holder, and to secure the cap in operative position, a wing-nut 43 engages the said holder and clamps said cap 75 upon the correspondingly contoured end of the bearing 26, as shown clearly by Figure 11. By the construction described, it will be apparent by reference to Figures 5 to 8 inclusive, that the saw blade 37 can be 80 secured to cut in the plane of the center of the back as shown in the first two figures mentioned, or can be arranged to cut in planes at opposite sides of and parallel with the center of the back as indicated by full 85 and dotted lines in Figure 7. If desired, the blade can also be arranged to cut at angles of forty-five degrees to the plane of the frame, as shown by Figure 8. To produce cuts in the plane of the center of the 90 back, the blade is secured on the lugs 35 at the side of the offset portion of the holder. When the blades are arranged to cut at opposite sides of such plane or obliquely with respect thereto, they are engaged with the 95 lugs 36 as indicated clearly by Figures 7 and 8. It is also obvious that if it is desired to make a horizontal cut while retaining the frame in a vertical position, the blade can be set on lugs 36, as shown by dotted lines, 100 Figure 6, or the same result can be obtained when the holder is positioned as shown in Figure 7, by setting the blade horizontal on lugs 35, as indicated by dotted lines in said figure. In both cases lateral pressure must 105 of course be applied on the handle. The use of the saw in the positions last mentioned will be required but seldom, but occasions will present themselves when a cut with the saw can be made in no other way, 110 and the same statement applies as to the use of the saw as shown by Figure 8, it being understood, of course, that the octagonal settings of the holders permit of the use of the saw with the blade reversed to present 115 its teeth toward the back of the frame. The cutting edge of the saw can be presented in eight different directions by proper rotatable adjustment of the holders. In Figure 7, the dotted lines L indicate a right-angle frame and dotted lines 1, a rod. By setting the blade offset with respect to the saw frame as shown by dotted lines, the rod 1 can be 120 cut substantially flush with the inner vertical face of frame L, without conflict between the latter and the back of the saw frame. In fact, by putting a light lateral strain on the blade it can be caused to cut flush with the inner face of frame L, a result practically impossible with an ordinary hack 125 130

saw, as the back thereof by contact with the frame L, would hold the blade a substantial distance from the vertical face of the frame.

It will be apparent that by adjustment of the clips 21-24, toward and from the back of the frame, the blades can be disposed different distances from the back, this arrangement permitting objects of different thickness or depth to be cut, it being also noted that if the angle arms 14 are reversed from the positions shown, that is, if the short ends are secured to the back and the long ends extend at right angles to the back, provision is made for a much wider range of adjustment as to distance between the back and the blade. It is apparent, of course, that the blade is held in place under a pulling strain applied at its rear end, and that this pulling strain holds the headed end of holder stem 32 in the octagonal socket 31, and that under the pulling strain exerted the tendency of the exposed ends of the angle arms 14 is to move toward each other and fulcrum upon the pins 13 and 18, the opposite portions of said angle arms therefore bearing against the closed end of the channeled back and channel members 3 and 8. It has been stated that the keepers are adapted to be adjusted upon the angle arms toward and from the back for the purpose of disposing the blade different distances from the back, and it will likewise be understood that said angle arms can be adjusted longitudinally of the back for the purpose of disposing their projecting ends at different distances apart to accommodate blades of different lengths. It will also be apparent that blades of different lengths can be accommodated by reversing the position of the bracket 20 with respect to its carrying angle arm, that is to say said bracket can be disposed as shown in dotted lines in Figure 20, this adjustment providing for the use of a hack saw of maximum length. If desired, the said bracket can be adjusted to said dotted position, and then the holder 33 can be removed from the bracket and mounted therein in reverse position. That is to say, by reversing the position of the bracket 20, the offset end 34 of the bracket is disposed adjacent the handle of the frame, but by also reversing said holder 33, so that the offset end shall underlie or stand in advance of the bearing 26, a saw blade of intermediate length may be used, it being understood that when this is done the cap 41 fits over the octagonal head 28 shown as inoperative in Figure 1.

To dispose the blade in close proximity to the back, the brackets 20 and 23 can be inverted as shown by dotted lines in Figure 1, but if the saw is to be used in a place where it would be impracticable to use the front angle arm 14, the latter and its bracket 23 and holder 32 will be discarded, and the

front end of the blade attached to the lug 11, the member 8 being adjusted longitudinally of the back if necessary on account of the length of the blade. With the arrangement last described, it is possible to sever an internal projection of a tube or opening provided the same is large enough to receive the back and blade. It is also possible to set the blade at different degrees of convergence with respect to the back, one of such positions being indicated by Figure 18. It is likewise obvious that with this arrangement of parts, blades of different lengths may be used.

In Figure 20, a modification appears in which one detachable part (8) is dispensed with and the enlarging of the back 3, at 4, is not necessary. The front end of the back, however, is formed to correspond with such end of the member 8, and is identified by similar reference characters as performing the same function. In this case the longitudinal adjustment to accommodate blades of different length must occur at the rear end only of the blade, as the front angle-arm 14 must bear a fixed relation to the pin 13 as regards movement longitudinally of the back of the frame, it being of course understood that it is practical to reverse the position of the bracket 23 on the front angle arm 14 to accommodate saws of different length.

From the above description it will be apparent that I have produced a device embodying the features of advantage enumerated as desirable in the statement of the objects of the invention, and while I have illustrated and described the preferred form of embodiment of the invention, it will be apparent that it is susceptible of modification in minor particulars without departing from the principle of construction or mode of operation involved.

I claim:

1. A hack saw comprising a back, a saw blade, a pair of angle blade holders connected to the opposite ends of said blade, a pair of arms each carrying one of said holders, said arms being mounted for independent adjustment along said back, and means connecting said arms and holders and permitting the latter to be inverted for positioning the blade-attaching ends of said holders either toward or away from said back and thereby varying the distance between said blade and back.

2. A hack saw comprising a back, a saw blade, a pair of arms independently adjustable longitudinally along the back, a pair of angle arms independently invertible and reversible respectively on the first-named arms for projecting their free ends toward or from the back and in the same longitudinal direction or toward each other, and angle holders rotatably adjustable on said angle

arms and detachably connected to said saw blades.

3. A hack saw comprising a back having a handle, a pair of arms depending from the back, angle arms slidably fitted at one end on said depending arms respectively, and having their other ends longitudinally alined, angle shaped holders rotatably mounted on the alined ends of the angle arms and relatively adjustable longitudinally, and a saw blade detachably connecting the said angle holders.

4. A hack saw comprising a back, a saw blade and spaced means on the back and supporting the blade in fixed relation to the back; the means nearest the rear end of the back having a longitudinally-adjustable element applying a pulling tension on the blade and reversible to accommodate blades of different lengths.

5. A hack saw comprising a back, a saw blade, means carried by said back and supporting the front end of said blade, an arm adjustable longitudinally along said back, an angle bracket carried by said arm, means connecting said arm to said bracket and permitting the latter to be inverted for positioning its blade-carrying end either toward or away from the back and also allowing said bracket to be projected either forwardly or rearwardly from said arm for accommodating blades of different length, and an adjustable blade-attaching element carried by said bracket and secured to the rear end of said blade.

6. A hack saw comprising a back, a saw blade, means carried by the back and supporting the front end of the blade, an angle arm adjustable on the back, a bracket secured on said angle arm, and a longitudinally-adjustable holder carried by the bracket and attached to the rear end of the blade and reversible to accommodate blades of different length.

45 7. A hack saw comprising a back, a saw blade, means carried by the back and supporting the front end of the blade, an arm on the back, a bracket adjustable on the angle arm toward and from the back, and a longitudinally-adjustable holder carried by the bracket and attached to the rear end of the blade, said holder being of angular form and also angularly adjustable about the axis of one of its end portions for variously positioning the blade with respect to said back.

8. A hack saw comprising a back, a saw blade, means carried by the back and supporting the front end of the blade, an angle arm adjustable on the back, a bracket on the angle arm and reversible to project forwardly or rearwardly therefrom, and a longitudinally-adjustable holder carried by the bracket and attached to the rear end of the blade.

65 9. A hack saw comprising a back, a pair

of brackets carried by said back, an angle blade-holding bracket carried by each of said first brackets, and a saw blade having its opposite ends connected to said angle brackets, said angle brackets being mounted for adjustment toward and away from each other and also rotatable about a common axis for positioning said blade in different angular relations to said back.

10. A hack saw, comprising a channeled back provided with notches in its lower edge, an angle arm with one end fitted in the channeled back and the other projecting from the lower edge thereof, and provided with a notch at the inner corner of the angle and a laterally-projecting pin engaging one of the notches of the back, a clip adjustable on the back and provided with a cross-pin engaging the notch of the angle arm, a saw blade, means secured to the front end of the blade and to the back, and means secured to the rear end of the blade and to the projecting end of said angle arm, the pull of the blade causing the angle arm to fulcrum on the cross-pin to hold the pin of the arm in the said notch of the back.

11. In a hack saw, a channeled back, having a cross-pin, a channeled extension fitting and slideable longitudinally in the back and provided with notches in its lower edge for selective engagement with the cross pin, and also provided at its front end with a cross-pin, an angle arm with one end fitted in said extension member and its other end projecting downwardly and having a notch at the inner corner engaging the cross-pin of the extension, a pair of alined holders fixed with relation to the back and relatively adjustable toward and from each other, one of them supported from the projecting end of the angle arm, and a saw blade connected at its ends to said holders.

12. A hack saw comprising a back having a handle, a pair of arms depending from the back, angle arms slidably fitted at one end on said depending arms respectively, and having their opposite ends longitudinally alined, angle shaped holders rotatably mounted in the alined ends of the angle arms, and relatively adjustable longitudinally, and a saw blade detachably connecting the other ends of said angle holders and capable through adjustment of the latter around a common axis, of facing in various directions with respect to such axis.

13. In a hack saw, a pair of arms having longitudinal tubular portions, a blade, angle holders attached to opposite ends of the blade and extending rotatably through the tubular portions of said arms respectively; one of the tubular portions at its end remote from the blade, being of angular form externally, a cap fitting non-rotatably on the angular end of said tubular portion and slidably but non-rotatably on the respective

holder, and means for securing the said holder and cap in fixed relation to each other and the angular end of the said arm.

14. In a hack saw, a pair of arms having

5 longitudinal tubular portions, a blade, angle holders attached to opposite ends of the blade and extending rotatably through the tubular portions of said arms respectively; one of the angle holders having a threaded 10 longitudinally-grooved stem extending through the tubular portion of a holder, and the latter at its end remote from the blade, being of angular form externally, an angular cap fitting non-rotatably on the angular 15 end of the tubular portion and slidably on the respective holder stem and provided with a tongue engaging the groove of said stem, and a nut engaging the stem and clamping the cap securely on the angular 20 end of the tubular portion of said arm.

15. In a hack saw, a back, a pair of arms having longitudinal tubular portions, a blade, angle holders attached to opposite ends of said blade and having stem portions 25 extending through the said tubular portions of the arms; one of the angle holders having an enlargement or angular head at its front end and the tubular portion of the corresponding arm an angular socket of larger 30 diameter than the bore of said tubular portion, and receiving said angular head and preventing turning thereof, means for preventing turning movement of the other holder, and means for adjusting it longitudi-

nally to tighten the saw and hold the angular head of the other holder clamped against the respective arm and within the angular socket thereof.

16. A hack saw, comprising a back, an arm projecting from and at an angle to the back, an angle bracket supported in fixed relation to the back and an angle bracket supported directly on the said arm or the back, angle holders rotatably carried by said angle brackets, and a saw blade connected 45 at its opposite ends to said holders.

17. A hack saw, comprising a back, an arm projecting from and at an angle to the back, an angle bracket supported in fixed relation to the back and an angle bracket 50 reversibly mounted on said projecting arm, angle holders rotatably and longitudinally adjustable on said angle brackets, and a saw connected at its ends to said holders respectively.

18. A hack saw, comprising a back, an arm projecting from and at an angle to the back, an angle bracket supported in fixed but reversible relation with respect to the back, an angle bracket reversibly mounted 60 on said projecting arm, angle holders rotatably carried by and adjustable longitudinally on said holders, and a saw blade connected at its ends to said holders.

In witness whereof I hereunto affix my 65 signature.

ALBERT G. VOLTZ.
